UNITED STATES PATENT OFFICE.

HARRY C. HAIGHT, OF CANTON, OHIO, ASSIGNOR TO THE AMERICAN FORGE AND MACHINE COMPANY, OF CANTON, OHIO, A CORPORATION OF OHIO.

METHOD OF FORGING INSULATOR CAPS.

Application filed May 7, 1923. Serial No. 637,173.

The invention relates to metal insulator caps used for supporting high tension conductors, and to the particular cup shaped type in which a slotted dome and a transverse partition forms a recess for receiving and engaging the head of a supporting bolt. The object of the improvement is to make the cap by a forging process, as distinguished from a casting process, and the new 10 method of making such a cap involves the forging of a cup shaped body, the separate forging of the dome shaped top, and then securing the dome to the cup by means of electric welding or the like.

15 The several steps of the process are illustrated in the accompanying drawings, forming part hereof, in which—

Figure 1 is a side elevation of an insulator, showing its head and cap in section;

20 Fig. 2, a perspective view of a cylindric blank from which the cup may be made;

Fig. 3, a sectional view of a punch and die by which the cup may be initially forged;

Fig. 4, a sectional view of a cup body as 25 the same is initially formed;

Fig. 5, a sectional view of a punch and die by which a rim groove may be formed;

Fig. 6, a sectional view showing the cup body with a rim groove formed therein;

30 Fig. 7, a sectional view showing a punch and die by which the dome body may be forged;

Fig. 8, a sectional view of the dome body as forged with a slotted opening, for receiving the head of a supporting bolt therein;

Fig. 9, a side elevation, one half in section, showing the dome body welded to the cup body;

40 Fig. 10, a top view of the completed cap; and

Fig. 11, a fragmentary sectional view showing the method of inserting a bolt through the slot into the dome recess.

45 Similar numerals of reference refer to similar parts throughout the drawings.

The cap 12 for the head 13 of an insulator 14 may be provided with a dome 15 on its closed end, having a slotted opening 16 in its top and forming a recess 17 for receiving the head 18 of a supporting bolt 19; and may be provided with apertures 20 in its side to receive a cotter pin 21 for pressing

the head of the bolt upward against the rim of the opening, all as shown in Fig. 1.

55 Such a cap may be made by initially forging from a cylindric blank 22 an inverted cup-shaped body 12', and at the same time forming an off-set 23 at the rim of the cup; which forging may be done by a punch 24 and a die 25, as shown in Fig. 3, and the off-set rim may be bent inward to form an internal annular groove 26 in the rim of the cup by means of a punch 27 and a die 28, as shown in Fig. 5.

60 A dome body 15 may be forged by a punch 29 and a die 30, as shown in Fig. 7, and the same may be formed with a slotted opening 16 as shown in Fig. 8. The rim of the dome may then be secured to the inverted 65 bottom of the cup by electric welding or the like, to complete the cap as shown in Fig. 9.

When the dome is secured to the cup by electric welding, a rib 31 or 31^a is preferably forged on each member to furnish 70 stock for the welding process.

75 The slotted opening 16 in the top of the dome 15 is formed with an elliptical opening centrally located in the top of the dome having a notch extending from one side 80 thereof, thus forming what may be termed a key-hole slot; the major axis of the elliptical opening being long enough to receive the head of the bolt by inclining the shank thereof to enter the notch, as shown in 85 Fig. 11.

90 After the head of the bolt has been entered into the recess 17 in the manner shown in Fig. 11, the shank is rotated so as to align the axis of the bolt with the axis of the cap, as shown in Fig. 1, whereupon the cotter pin 21 may be entered through apertures 20 provided for that purpose for holding the bolt in the position shown in Fig. 1.

95 This formation of a key-hole slot in the top of the dome, permits the dome body 15 to be made without any breaks in its peripheral portion, so that the entire circumference or rim of the same may be joined to the closed end of the cup, thus giving the maximum strength to the insulator and especially to the walls of the recess socket in which the bolt head is received and secured.

I claim:

100 1. The method of making an insulator cap or the like, which includes forging an in-

- verted cup body and forging a separate dome body with a continuous rim and a key-hole slot in its top, and then welding the rim of the dome to the inverted bottom of the cup.
- 5 2. The method of making an insulator cap or the like, which includes forging an inverted cup body and forging a separate dome body with a continuous rim and a key-hole slot in its top, and then welding the rim
- 10 of the dome to the inverted bottom of the

cup, there being an annular rib forged on each member to furnish stock for welding them together.

3. The method of making an insulator cap or the like, which includes forging an inverted cup body and forging a separate dome body with a rim thereon and slot therein, and then welding the rim of the dome to the inverted bottom of the cup.

HARRY C. HAIGHT.
